NUT-HOLDING SOCKET WRENCH

Harry E. Strunk, Berkeley, Calif.

Application April 25, 1949, Serial No. 89,509

1 Claim. (Cl. 81—125)

1

This invention relates to socket wrenches of the type disclosed in my pending application Serial No. 662,237 filed April 15, 1946 and now abandoned.

It is frequently necessary to apply nuts to or remove them from machine screws, bolts, studs or the like located at points inaccessible to a person's hands or fingers in the assembly and servicing of complicated apparatus such as radio sets, instrument panels on airplanes, motor vehicles, and the like, engines and other machines. While long and slender shank socket wrenches have been employed in doing such work, it frequently happens that the nut is dropped from the wrench socket and into the mechanism so that much time is lost in recovering it. The invention contemplates a wrench of this character having manually actuated means for holding a single nut in the socket and for releasing it.

The object of the invention is to provide a nut-holding socket wrench which is of extremely simple construction, having only one movable part, which is light in weight yet strong and sturdy so as it will not be likely to get out of order, and which may be operated entirely by one hand of the user to pick up a nut from a bench or the like and apply it to a relatively inaccessible screw, or to remove a nut from such a screw and retain the nut in the wrench socket until it is manually discharged from the socket.

The above and other objects and advantages will be apparent from the following detailed description of the present preferred embodiment of the invention shown in the accompanying drawings in which:

Fig. 1 is a side elevation of the wrench.

Fig. 2 is a central longitudinal sectional view.

Fig. 3 is a detail section on an enlarged scale through the socket end of the wrench and showing a nut in the socket.

Fig. 4 is a view similar to Fig. 3 showing a nut about to be applied to a relatively inaccessible screw, and

Fig. 5 is an end view of the wrench.

Referring more in detail to the drawings, the numeral 10 denotes the tubular shank or body of the wrench which is shown as formed at its rear end with an enlarged integral socket portion 11. The elongated shank which is made of a suitable metal may be coated with a plastic electric insulation but as shown its front portion has an enlarged cylindrical hand grip 12 of wood, plastic or other material. The outer surface of the hand grip portion may be knurled, serrated or otherwise formed to prevent the tool from slip-

2

ping in the hand. In the portion 11 is formed an outwardly open nut receiving socket 13 of a size to receive a single nut. The socket may be of hexagonal shape as seen in Fig. 5, or it may be a twelve point socket or of any other shape to engage the flat outer face or faces of a nut. In depth the socket is substantially the height or thickness of the nut so that the latter substantially fills the socket and one of the ends of the nut will abut the bottom wall 14 of the socket as shown in Figs. 3 and 4. The shank or body 10 is formed with a through bore or passage 15 which is preferably cylindrical and of uniform diameter. The front end of the bore 15 opens through the wall 14 of the socket, the bore being concentric with the threaded bore or hole through the nut and of the same diameter or slightly larger as seen in Fig. 3.

For the purpose of holding the nut in the socket 13 I provide a manually operable plunger 16 in the bore of the tubular shank. The plunger extends beyond the rear end of the shank and may be provided with an operating knob or head 17 to abut said end and limit the inward movement of the plunger as seen in Fig. 2. The plunger is of such length that its front end projects about half-way into the socket 13 when the combined finger piece and top 17 engages the rear end of the shank. The knob may be threaded on the plunger or otherwise attached and it is preferably of cylindrical shape with its outer surface knurled or serrated. In order to frictionally retain the nut in the socket when the parts are in the position shown in Figs. 2 and 4, the plunger has at least at its front end a resilient and laterally deflected portion 18 which frictionally engages the screw threads in the nut. Preferably the entire plunger is formed from a cylindrical resilient metal rod of uniform diameter which is bowed or curved longitudinally from end to end so that it has a three point contact with the bore 15 of the shank. In other words the plunger rod 16 is so shaped and tensioned that its front end portion will engage the bore at 19 close to the front end of the shank, its rear end portion will engage the bore close to its rear end or the threads in the nut as seen in Figs. 3 and 4, and the center or some intermediate portion, as at 20, will engage the wall of the bore between the ends of the latter. It will be noted that both the bore and the rod have uniform diameters or cross-sectional shapes, and since the rod is permanently and uniformly bowed throughout its length, its end portions will engage the same side of the bore at longitudinally spaced end portions thereof while

the central portion of the rod engages the central portion of the opposite side of the bore. The end portion 18 may be formed with a rounded head to facilitate its entrance into the bore of the nut when the knob is pushed down against the front end of the shank but I preferably bevel said end as at 21. The plunger rod may be entirely withdrawn from the bore of the shank if desired so that the tool may be used as an ordinary socket wrench, but the three point frictional engagement of the rod with the shank bore will hold it in the shank at various positions.

In using the tool the rod is moved by manipulating the finger knob 17 to position the beveled end 18 in the bore as seen in Fig. 3. The socket 15 may then be placed over a nut on a bench, table or other support and the knob is then moved against the rear end of the shank to cause the beveled end of the rod to spring into the nut and frictionally engage the threads of the same as shown in Fig. 4. The nut is then threaded on a screw S which might be in the bottom of a small recess R in a part P as in Fig. 4. As the nut is turned down upon the screw the latter will push the rod out of the nut, and since the rod may slide upwardly to any extent in the shank it is immaterial to what extent the screw may project through the nut. In removing the nut from the screw, the end 18 of the rod will be moved into the shank bore, and after the nut is almost off of the screw, the finger knob is moved downwardly to cause the end 18 to enter the nut and frictionally retain the latter in the socket until released by upward movement of the end 18 into the bore 15.

It will be seen that the tool is extremely simple having but one movable part, and hence may be made at a small cost. The shank may be made of tubing of uniform diameter inside and out. In addition the tool is light in weight but very strong and sturdy so that it is not likely to get out of order. It may be operated entirely by one hand leaving the other free to hold the device or apparatus being assembled or serviced. It has been found that the tool will save a great deal of time since it may be used to pick up a nut from a bench and apply it to a screw, or to remove a nut from a screw and retain it in the socket until released. The construction is such that tool may

be used in places inaccessible to the user's hands or fingers and there is no danger of the nut accidentally dropping from the socket into an intricate mechanism or a place from which it would be difficult to reach the nut.

While one preferred embodiment of the invention has been shown and described in detail, it is to be understood that variations in the form, proportion and arrangement of parts are possible and contemplated within the spirit of the invention and the scope of the claim which follows.

I claim:

A nut applying and removal wrench comprising a slender tubular shank having at its front end a forwardly open nut socket to receive a single nut and prevent it from rotating in said socket, said shank having a straight, through bore of uniform cross-sectional shape which opens into the bottom of said socket, a manually operable, nut retaining and releasing plunger longitudinally movable in the bore of said shank and frictionally retained therein, said plunger comprising a single resilient rod of uniform cross-sectional shape and of a length greater than the length of said bore, said resilient rod having a permanent longitudinal bow from end to end to cause its end portions to frictionally engage end portions of said bore at longitudinally aligned points on one side of said bore while its central portion frictionally engages the opposite side of said bore adjacent the central portion of the latter, said rod having its front end provided with a beveled portion to enter and frictionally engage the threads in a nut in said socket, and a combined finger piece and stop on the projecting rear end of said rod engageable with the rear end of said shank to limit the movement of said beveled front end of said rod into the nut.
